his ATTY

UNITED STATES PATENT OFFICE.

LOUIS FLORI, OF BOULOGNE SUR SEINE, FRANCE.

PRESS FOR DRYING AND IRONING WEARING LINEN.

Application filed December 8, 1925, Serial No. 74,021, and in France December 24, 1924.

This invention has reference to new and useful improvements in the known type of press for drying and ironing linen and more particularly wearing linen constituted by 5 two cooperating steam-heated tables: a stationary buck on which are spread the pieces of linen to be dried and ironed and a movable pressure head adapted to be brought in contact with the said stationary buck so as 10 to squeeze between the buck and head the said pieces of linen and thus to perform the drying and ironing operations.

A primary object of the invention is to provide a drying and ironing press of the 15 type set forth wherein the lever adapted for operating the pressure head is provided with means both for balancing the weight of said head and for adjusting the pressure to be exerted thereby upon the stationary buck 20 and consequently upon the linen spread upon same for obviating any wrinkling or rumpling of whatever protruding parts such linen may comprise.

A further object of the invention is to provide a drying and ironing press of the type 25 set forth comprising particularly when it is utilizable for drying and ironing such articles as men's shirts a special protruding device adapted for inwardly and outwardly 30 maintaining or guiding in a stretched condition the collar or other projecting part of the shirt or other similar article of linen whilst the upper or movable table squeezes said shirt upon the stationary table.

35 With these and other objects in view as may appear in the following description, the invention comprises the novel construction and arrangement of parts operating as will readily appear with reference to the accompanying drawing wherein:

Fig. 1 is an elevational view showing the 40 drying and ironing press in its closed position, i. e. when its buck and pressure head are in contact for squeezing the linen placed therebetween.

Fig. 2 is a similar elevational view but showing the press in its opened position, i. e. when the pressure head is lifted away to its full extent from the stationary buck.

50 Fig. 3 is a plan view of another buck form.

Fig. 4 is a plan view of the stationary buck specially adapted for drying and ironing men's shirts or similar articles, assuming the

collar stretching device to be in its operative position.

55 Fig. 5 is an elevational view of the stationary buck shown in Fig. 4 but assuming the collar stretching device to be in its inoperative position.

Fig. 6 is a sectional elevational detailed 60 view drawn to a larger scale of the collar stretching device according to the construction of stationary buck shown in Figs. 4 and 5.

Fig. 7 is a plan detailed view of same. 65

Reference being now had to these figures wherein like references designate like parts, the press, according to the invention, comprises, as usual, two cooperating hollow tables 1 and 2 having varying size and shape 70 appropriated to the conformation of wearing linen to be dried and ironed. The table or buck 1 is stationary and its upper surface adapted for receiving the linen to be dried and ironed is coated throughout its extent 75 with a piece of treble-milled flannel 1^a. The companion table or pressure head 2 is movable, i. e. adapted for being lifted away from said stationary buck and for being easily brought in contact therewith; its surface adapted for contacting with the linen is polished and conveniently nickelized. Within each of these tables circulates steam which is fed thereto by separate pipes of conventional construction (not shown). On the 80 upper external face of the pressure head 2 is suitably fixed a large goose-neck shaped arm 4 pivotally mounted upon a spindle 5 rotatably mounted at a certain distance above a supporting frame A in bearings 6; beyond 85 said spindle 5 the arm 4 has a rear extension 4^a integral therewith provided at its free end or adjacent thereto with a counterweight 3 so reckoned as to properly balance the weight of the pressure head 2. 90

95 At a relatively small distance from the arm 4, its extension 4^a is traversed by a spindle 8 upon which is pivotally mounted an elongated lever 7 extending in overhanging relation over the pressure head 2 for compressing the latter downwards and having a short extension 7^a acting as a link and jointedly secured at its free end upon the upper end of a rod 10 through the intermediary of a pin 9; said rod 10 has its lower end 100 pivotally mounted upon a spindle 12 rotata- 105

bly mounted in stationary bearings 13 which may for instance be secured to the rear legs B of the supporting frame A. In order to adjust the length of the rod 10, a tensioning 5 nut 11 or a similar device such as a turn-buckle is arranged intermediate its ends, i. e. between the pin 9 and the spindle 12. By this arrangement, the adjustable rod 10 and the lever 7—7^a constitute in some sort a toggle device whereby a regulatable pressure 10 may be exerted upon the pressure head 2 and consequently upon the linen spread on the flat on the buck 1.

When the pressure head 2 is lifted away 15 to its full extent from the buck 1, the lever 7—7^a and the rod 10 constituting the aforesaid toggle device substantially afford relatively to the goose-neck shaped arm 4 and to its rear extension 4^a carrying the counter- 20 weight 3 the positions shown in Fig. 2. As will be readily understood, by lowering the fore part 7 of the lever 7—7^a, the pressure head 2 is brought down in contact with the buck 1 (see Fig. 1) and presses same with a 25 determined pressure the intensity of which may be regulated at will according to drying or ironing requirements simply by suitably adjusting the tensioning nut 11 or equivalent device along the rod 10.

30 In Fig. 3 is illustrated by way of example one form of trapezoidal table having rounded corners utilizable for flat pieces of linen. The shape of the buck and pressure table will of course vary according to the various 35 kinds of linen articles to be dried and ironed.

The form of buck 1 illustrated in Fig. 4 40 has steam circulating ducts *v* imbedded therein, the steam being admitted at *a* and escaping at *s*. It is specially adapted for drying and ironing men's shirts or similar articles. To that effect, it has a correspondingly sized rectangular shape and rounded corners and moreover comprises on its upper face a collar stretching device.

45 The collar stretching device shown in Figs. 4, 5, 6 and 7 and more in detail although fragmentarily in Figs. 6 and 7 is constituted by the combination of a semi-circular upstanding rib *b*' located in a horse-shoe 50 shaped notch *b* cut out in the side edge of the buck 1 and secured concentrically thereto as shown in Fig. 7, a longitudinally sliding member terminated outwardly by an upstanding transverse blade or web 16 and sub- 55 mitted to the action of an antagonistic coil spring 16^a, and a spring pawl operable by a stud 15 the operative end of which engages a groove formed in the longitudinal slide for overcoming the stress of the spring when 60 it is desired to stretch out the shirt collar around the rib *b*' and the web 16.

The pedestal *p* (Fig. 5) is carried upon a base-plate 17 suitably secured upon the supporting frame A. At the end of said base-plate 17 corresponding to the collar stretch-

ing device is fixed an upstanding bracket 18 in which is pivotally mounted a lever 19 forced outwardly by a spring plate 20 and bifurcated at its upper end to swingingly carry a horse-shoe shaped shackle 21 provided with a handle 22. By rocking down this shackle 21 to bring same in contact with the parts of the collar stretcher as above described, said shackle is made to encompass the shirt collar which is thus maintained in its stretched position both inwardly and outwardly throughout the drying and ironing operations as performed by the cooperation of the buck and pressure head 1 and 2, whereby the shirt collar or analogous protruding part of the article of wearing linen is perfectly ironed according to the required shape without becoming wrinkled or rumpled.

Whilst, in accordance with the patent statutes, a convenient embodiment of the invention has been described in the foregoing with reference to the accompanying drawing, it will be appreciated that numerous minor 85 constructional details might be changed by anyone skilled in the art without departing from the scope of the invention as determined by the subjoined claims.

What I claim and desire to secure by Letters Patent is:—

1. A press of the type set forth for drying and ironing linen, comprising in combination a frame, a stationary buck to receive the linen, a pressure head arranged over the buck, steam ducts imbedded in said buck and head for heating purposes, an arcuate arm rigidly secured to said pressure head and pivotally mounted on the press, said pivotal mounting comprising a transverse spindle supported rearwardly of the buck, a counterweight carried by an integral rearward projection of said arm, a second transverse spindle supported in the latter projection of the arm, and a bell crank lever pivoted on the second transverse spindle and at one end extending over the pressure head, the opposite end of the lever being pivoted to a link pivoted on the press.

2. A press of the type set forth for drying and ironing wearing linen comprising, in combination, a supporting frame, a stationary buck on which may be spread the piece of linen, a movable pressure head adapted for being lifted away from said buck, means for heating said buck and head, a goose-neck shaped arm rigidly secured upon said head and pivotally mounted rearwardly of the same on a transverse spindle carried by the press frame, a counterweight terminally fitted on a rearward integral extension of said arm, a second spindle traversing said extension at a small distance from said arm, a two-armed arcuate lever pivotally fulcrumed intermediate its ends upon the latter spindle, one arm of said

- lever operating over the pressure head, a rod pivotally secured at its upper end to the other arm of the lever and pivotally secured at its lower end to the press frame, whereby an operation of the lever causes the arm to press the head upon the buck, and means for adjusting the length of said rod and cause the combination of the same with the lever to act as a toggle-device whereby the pressure exerted by said arm and lever upon the head may be regulated at will.
3. A press of the type set forth for drying and ironing wearing linen comprising, in combination, a supporting frame, a stationary buck on which may be flatly spread the piece of linen, a liftable pressure head arranged over the buck, means for heating said buck and head, a transverse spindle mounted in bearings carried by the frame, a goose-neck shaped arm rigidly secured upon the head and pivotally carried by the spindle, a rearward cranked extension formed integral with said arm adjacent said spindle, a counterweight terminally fitted on said extension, a second spindle traversing said extension at a small distance rearwardly of said arm, a two-armed arcuate lever pivotally fulcrumed intermediate its ends upon the latter spindle, one arm of said lever operating over the pressure head, a rod pivotally secured at its upper end to the other arm of the lever and pivotally secured at its lower end to the press frame whereby an operation of the lever causes the arm to press the head upon the buck, and a turn-buckle device intermediate the ends of the rod for adjusting its length and permitting the pressure of the lever associated with the rod to be regulated at will.
- In testimony whereof I affix my signature.

LOUIS FLORI.
